(57) **CLAIM**

The ornamental design for an overshoe for athletic shoes, as shown and described.

DESCRIPTION

FIG. 1 shows a perspective view of an overshoe for athletic shoes;

FIG. 2 shows a right elevation view of the overshoe for athletic shoes of FIG. 1;

FIG. 3 shows a left elevation view of the overshoe for athletic shoes of FIG. 1;

FIG. 4 shows a top view of the overshoe for athletic shoes of FIG. 1;

FIG. 5 shows a bottom view of the overshoe for athletic shoes of FIG. 1;

FIG. 6 shows a front view of the overshoe for athletic shoes of FIG. 1; and,

FIG. 7 shows a back view of the overshoe for athletic shoes of FIG. 1.

The broken lines illustrate environmental structure and form no part of the claimed design.
